(57) **ABSTRACT**

The invention provides a practice device for practicing the game of golf. The practice device includes a ball, and a tether affixed to the ball for limiting the travel of the ball. The practice device also includes a reel for receiving the tether. The reel can include a lock for preventing the rotational movement of the reel. An anchor is provided for securing the practice device to a surface. The anchor has at least one leg. In an embodiment, the anchor includes two legs, each leg having a distal end and a proximal end. The proximal ends of the legs are joined by a substantially perpendicular cross member, and the distal ends of the legs are receivable into the surface. The reel is rotatably secured to the anchor. The invention can also include a loop secured to the anchor for guiding the tether. The invention can additionally include deflector for preventing the ball from hitting the reel or the anchor.

GOLF GAME PRACTICE DEVICE

TECHNICAL FIELD

The invention relates to the field of sports equipment. More specifically, the invention relates to a practice device for the game of golf.

BACKGROUND OF THE INVENTION

The game of golf has become increasingly popular in recent years. More people are playing the game, and as a result, methods and devices for improving a player's skill in the game have become more desirable.

To practice the game of golf, a player typically pays to hit practice balls at a driving range at a public or private golf course. Alternatively, the player may use a golf game practice device which allows the hitting of a golf ball, while limiting the distance the golfball will travel. The use of a practice device is often desirable because a player can use the device at any desired location as time permits, eliminating the need to travel and to pay fees to a commercial driving range.

As early as 1912, attempts were made to provide practice devices for the golf enthusiast, as evidenced by U.S. Pat. No. 1,014,122 to Kip. Kip discloses a golf ball that is securable to a tether for use in practice play. Several other U.S. patents also disclose practice devices. The devices generally include a base, a tether secured to the base, and a ball secured to the tether. Examples include U.S. Pat. No. 1,504,752 to Green, U.S. Pat. No. 1,528,909 to Bullard, and U.S. Pat. No. 1,700,224 to Hendersen.

In U.S. Pat. No. 3,502,337, inventor Butkus discloses a practice device of the type described above. As an improvement, the Butkus '337 device includes an elasticized tether. In U.S. Pat. No. 3,521,887, Butkus further discloses a tether of variable length. U.S. Pat. No. 5,054,786 to Solomon provides a practice device in which the tether includes both elastic and non-elastic segments. The length of the elastic segment can be adjusted to vary the distance the ball travels.

While the above patents describe golf game practice devices which are functional, a need exists for a new golf game practice device that solves several problems not addressed by the known devices. For example, while some of the known devices provide a tether of variable length, the amount of variability is limited. Furthermore, in those devices where a relatively long tether is provided, storage of the device is problematic, because the tether can easily become tangled. Conversely, if a relatively short tether is provided, the player is limited as to the types of shots he can practice. A short tether does not allow the ball to travel its full trajectory on long drives, so the player can not see how adjustments to his stance and swing ultimately affect the distance and course of the ball.

SUMMARY OF INVENTION

A golf game practice device is disclosed. The golf game practice device includes a ball, and a tether affixed to the ball for limiting the travel of the ball. The practice device also includes a reel for receiving the tether. An anchor is provided for securing the practice device to a surface. The anchor has at least one leg, and the leg has a distal end and a proximal end. The distal end of the leg is receivable into the surface. The reel is rotatably secured to the anchor.

In an embodiment of the invention, the anchor includes two legs, each leg having a distal end and a proximal end.

The proximal ends of the legs are joined by a substantially perpendicular cross member, and the distal ends of the legs are receivable into the surface. The reel is rotatably secured to the anchor.

5 In an embodiment, the invention further includes a loop secured to the anchor for guiding the tether.

In an additional embodiment, the invention includes a handle on the reel for rotating the reel.

10 In a further embodiment of the invention, the reel includes a lock for preventing rotational movement of the reel.

In another embodiment of the invention, a deflector is provided for preventing the ball from hitting the reel or the anchor.

15 According to the invention, a golf game practice device having a tether of variable length is provided. The features and advantages of the invention will be made clear by the description and drawings that follow.

BRIEF DESCRIPTION OF DRAWINGS

FIG. 1 is a perspective view of the golf game practice device of the present invention;

20 FIG. 2a is an end view of the golf game practice device of the present invention;

FIG. 2b is a side view of the golf game practice device of the present invention;

FIG. 2c is an end view of the golf game practice device of the present invention;

30 FIG. 3 is an exploded partial perspective view of the golf game practice device of the present invention;

FIG. 4 is a perspective view of an embodiment of the golf game practice device of the present invention; and

35 FIG. 5 is a perspective view of a player using the golf game practice device of the present invention.

DETAILED DESCRIPTION OF SPECIFIC EMBODIMENTS

40 The invention comprises a golf game practice device 20, referred to hereinafter as simply the "practice device," as shown in FIGS. 1 through 5. The practice device includes a ball 30, a tether 40, a reel 50, and an anchor 90. In an embodiment, the practice device also includes a deflector 110 as shown in FIG. 4.

45 The ball 30 of the practice device is preferably a conventional golfball that has been adapted to be secured on the tether 40. Various methods of securing the ball to the tether are known. In one preferred method a bore 32 is provided through the center of the ball, and the tether is passed through the bore, as shown in FIG. 1. A retaining device such as a knot, washer, plug or other device is employed to retain the ball on the tether. Other methods of securing the ball to the tether may also be used, and are considered to be within the scope of the invention.

50 The tether 40 of the practice device is preferably a length of high tensile strength cord. Most preferably, the tether is a length of parachute cord. The inventor has had success with 550 pound test parachute cord, although other weights and 60 types of cords would be suitable, providing that the cord will not break when the ball 30 is hit.

55 The reel 50 of the practice device 20 is secured to the anchor 90. The reel serves several purposes. The reel provides a convenient way to store the tether 40. When the tether is wound on the reel it will not become tangled or knotted, and will be readily available for use. The reel also provides a way to adjust the length of the tether. This is a

valuable feature, because it allows the user to limit the distance the ball will travel when hit. The user can use the device in a confined area, such as a backyard or park, without fear of damaging nearby buildings, vehicles, etc. Additionally, the reel allows the user to accurately simulate long drives. For example, by paying out 75 feet of tether from the reel, the user can practice drives as long as 150 feet. The travel of the ball **30** will not be stopped short by the tether, so the user can observe the trajectory and hook or slice of the ball, as is possible at a commercial driving range.

Another purpose of the reel **50** is to provide a tidy and convenient way of bringing in the ball **30** after it is hit. Usually, the user will walk to the place where the ball landed, and hit the ball again from that location. At the conclusion of a practice session, however, the reel provides a convenient mechanism for bringing in the ball while neatly stowing the tether **40**.

In a preferred embodiment of the invention, the reel **50** includes a rotatable spindle **52** having a first end **54**, a second end **56**, a first end rim **58** and a second end rim **60**, as shown in FIG. 3. A first spindle receiving aperture **62** in the first end rim and a second spindle receiving aperture **64** in the second end rim are sized to receive the spindle first and second ends, respectively. Set screws **66** secure the first end rim and the second end rim to spindle. When the set screws are secure, they prevent lateral movement of the spindle. Other devices for holding the spindle in position are also contemplated, and considered to be within the scope of the invention. A first spindle mount **68** and a second spindle mount **70** are secured to the anchor **90**. The first end of the spindle is rotatably received in the first spindle mount, and the second end of the spindle is rotatably received in the second spindle mount. Preferably, the reel **50** also includes a handle **72** for turning the reel, as detailed in FIGS. 2a and 2b. The handle is preferably secured to the first end of the spindle.

In an embodiment, the reel **50** also includes a lock **74**. When engaged, the lock stops the rotary motion of the reel. The user can pay out a desired amount of tether **40**, lock the reel, and thus limit the distance the ball **30** will travel when hit. The lock can also be employed when the tether has been wound on the reel for storage, to prevent the tether from unwinding. There are various known means of locking a reel to prevent it from rotating. In the embodiment shown in the drawings and detailed in FIG. 3, the lock includes a pin **76**, a mount pin receiving aperture **78** and a spindle pin receiving aperture **80**. When the anchor pin receiving aperture and the spindle pin receiving aperture are aligned, the pin can be inserted therethrough to prevent the reel from rotating. Other reel locking means may also be employed, and are considered within the scope of the invention.

Preferably, the spindle **52** further includes an aperture **82** for receiving an end of the tether **40**. The end of the tether is passed through the aperture and knotted to secure the tether to the spindle. Any method of securing the tether to the spindle can be used as an alternative to the aperture **82**.

It will be appreciated that there are various known reel-type devices which would fulfill the requirements of the practice device **20** described herein. Furthermore, various mounting configurations can be used to secure the reel in position, including configurations which secure the reel in a position other than the horizontal orientation shown in the drawings and described herein. Therefore, the reel **50** may be any device which can take up and pay out the tether **40** as required by the invention.

The anchor **90** of the practice device **20** is shown in FIGS. 1 through 5. The anchor provides an attachment point for the

reel **50** and also secures the practice device to a surface. In most instances, the surface will be a ground surface such as soil, dirt, sod, gravel, sand, or a combination thereof. The anchor includes at least one leg, and preferably includes at least two legs spaced apart from and parallel to one another. In a preferred embodiment, and as shown in the drawings, the anchor includes a first leg **92**. The first leg has a distal end **94** and a proximal end **96**. The anchor further includes a second leg **98**. The second leg has a distal end **100** and a proximal end **102**. A substantially perpendicular cross member **104** joins the first leg to the second leg. Preferably, the cross member is affixed to the proximal ends of the first leg and the second leg. The first leg, the second leg, and the cross member preferably form a single contiguous unit. The distal end of each leg can have a chiseled or sharpened tip to facilitate pushing the anchor into the ground.

The first spindle mount **68** and the second spindle mount **70** are secured to the anchor **90** at the first leg **92** and the second leg **98**, respectively. In a preferred embodiment, the first spindle mount and the second spindle mount are positioned near the proximal ends **96**, **102** of the first and second legs, respectively.

In an embodiment, the anchor **90** also includes a loop **106** for guiding the tether **40** as it is wound or unwound on the reel **50**. Preferably, the loop is positioned at the approximate center of the cross member **104**. The loop has a smaller diameter than the ball **30**, so the ball and attached tether cannot be pulled through the loop. The loop thus provides a stop against which the ball rests when the tether is fully wound on the reel. The tether is secured to the ball, and cannot unwind from the reel when the lock **74** is engaged.

In an additional embodiment of the invention, a deflector **110** is provided, as shown in FIG. 4. The deflector can be placed over the practice device **20** when in use, to prevent the ball **30** from hitting the practice device and bouncing back, potentially injuring the user. The deflector comprises a substantially rigid first panel **112** having a first panel upper edge **114**, and a substantially rigid second panel **116** having a second panel upper edge **118**.

The first panel **112** and the second panel **116** are hinged together at their respective upper edges **114** and **118**, as shown in FIG. 4. The upper edge of the first panel includes a first panel notch **120**, and the upper edge of the second panel includes a second panel notch **122**. The first panel notch and the second panel notch are substantially aligned. Most preferably, the opening **124** created by the first panel notch and the second panel notch is sized to allow the passage of the ball **30** therethrough. The deflector is preferably made from a low friction, impact resistant material that is also weather proof and lightweight. Ultra high molecular weight (UHMW) plastic has been used successfully for the deflector material.

In use, the practice device **20** provides a simple yet very effective method of practicing the game of golf. The user secures the practice device to a surface such as the ground, as discussed above, by pushing the legs **92** and **98** of the anchor **90** into the ground. The lock **74** is disengaged to allow the reel **50** to rotate. The tether **40** is then unwound from the reel to a desired length, and the lock engaged to stop the rotation of the reel. The practice device is ready for use.

The user of the practice device **20** can unwind the tether **40** to a length appropriate for long drives. For example, the tether can be unwound to 50 feet, so that the ball **30** is 50 feet away from the anchor **90**. The user can then hit the ball using a golf club, and the ball will travel as far as 100 feet. The

user can observe the trajectory of the ball, and make adjustments to stance and swing the next time the ball is hit.

Alternatively, the user of the practice device **20** can unwind the tether **40** to a limited length, as determined by obstacles in the area. For example, if the practice device is being used in a residential area, the user may limit the length of the tether to avoid reaching buildings, vehicles, neighboring property, and the like. The user can then hit the ball using a golf club, without fear of damaging the nearby buildings or vehicles, or sending the ball onto neighboring property.

When the user has concluded a practice session using the practice device **20**, the lock **74** on the reel is disengaged, and the tether is **40** wound back on the reel by using the handle **72** to rotate the reel. When the tether is completely wound, the ball **30** attached to the tether will abut the loop **106** and prevent the reel from being rotated any further. The lock **76** is then engaged to prevent the reel from rotating in either direction. The reel is thus secured, and the practice device **20** is neatly stored until the next use.

The method of using the invention can further include the step of positioning the deflector **110** in a tent-like manner over the practice device **20** after the practice device has been secured in the ground or other surface. The ball **30** and tether **40** are passed through the opening **124** of the deflector before extending the tether to its desired length. In the event that the ball is inadvertently directed at the anchor **90** or reel **50**, the deflector provides a surface off of which the ball can be deflected. The smooth sloped surface provided by the first panel **112** and the second panel **116** will cause the ball to bounce slightly, but continue in the general direction in which the ball was hit.

In compliance with the statutes, the invention has been described in language more or less specific as to structural features and process steps. While this invention can be embodied in different forms, the specification describes and illustrates preferred embodiments of the invention. It will be understood that this disclosure is an exemplification of the principles of the invention, and is not intended to limit the invention to the particular embodiments described. Those with ordinary skill in the art will appreciate that other embodiments and variations of the invention, which employ the same inventive concepts as the invention, are possible. Therefore, the invention is not to be limited except by the following claims, as appropriately interpreted in accordance with the doctrine of equivalents.

What is claimed is:

1. A golf game practice device, the practice device including:
  - a ball;
  - a tether affixed to the ball for limiting the travel of the ball;
  - a reel for receiving the tether; and
  - an anchor for securing the practice device to a surface, the anchor including a first leg and a second leg, each leg having a distal end and a proximal end, the distal ends

receivable into the surface, and the proximal ends joined by a cross member; and

the reel rotatably secured to the anchor.

2. The practice device of claim 1, further including a loop secured to the anchor for guiding the tether.

3. The practice device of claim 1, the reel further including a handle for rotating the reel.

4. The practice device of claim 1, the reel further including a lock for preventing rotative movement of the reel.

5. The practice device of claim 1, further including a deflector for preventing the ball from hitting the reel or the anchor.

6. The practice device of claim 1, the reel including:

a spindle, the spindle having a first end and a second end; a first rim secured proximate the first end of the spindle, the first rim having a first spindle receiving aperture; a second rim secured proximate the second end of the spindle, the second rim having a second spindle receiving aperture;

a first spindle mount affixed to the anchor for receiving the first end of the spindle; and

a second spindle mount affixed to the anchor for receiving the second end of the spindle.

7. A golf game practice device, the practice device including:

an anchor, the anchor having a first leg, a substantially parallel second leg, and a substantially perpendicular cross member joining the first leg to the second leg;

a ball;

a tether affixed to the ball for limiting the travel of the ball; and

a reel for receiving the tether, the reel including a spindle, the spindle having a first end and a second end; a first rim secured proximate the first end of the spindle, the first rim having a first spindle receiving aperture;

a second rim secured proximate the second end of the spindle, the second rim having a second spindle receiving aperture; a first spindle mount affixed to the first leg of the anchor for receiving the first end of the spindle; and

a second spindle mount affixed to the second leg of the anchor for receiving the second end of the spindle.

8. The golf game practice device of claim 7, further including a lock for preventing rotational movement of the reel.

9. The golf game practice device of claim 8, in which the lock comprises a pin, a mount pin receiving aperture formed in the second spindle mount, and a spindle pin receiving aperture formed in the second end of the spindle, such that the mount pin receiving aperture and the spindle pin receiving aperture are alignable, and the pin is receivable in the mount pin receiving aperture and the spindle pin receiving aperture to prevent rotational movement of the reel.
